[57] **CLAIM**

The ornamental design for a combined stationary table and rotatable lounge seating unit, as shown and described.

DESCRIPTION

FIG. 1 is an exploded front perspective view of a combined stationary table and rotatable lounge seating unit showing my design.

FIG. 2 is a front elevational view of the assembled components;

FIG. 3 is a plan view;

FIG. 4 is a right side elevational view;

FIG. 5 is a rear elevational view;

FIG. 6 is an exploded perspective view showing the principal components of a modification of my new design shown in FIGS. 1 to 5;

FIG. 7 is a front elevational view of the assembled components shown in FIG. 6;

FIG. 8 is a plan view thereof;

FIG. 9 is a right side elevational view; and

FIG. 10 is a rear elevational view.

Fig. 3Fig. 2Fig. 4

Fig. 5

Fig. 6.Fig. 8.Fig. 7.Fig. 9.

Fig. 10.
